UNITED STATES PATENT OFFICE.

HARRY C. NAILL, OF HANOVER, PENNSYLVANIA, ASSIGNOR TO LONG FURNITURE COMPANY, OF HANOVER, PENNSYLVANIA, A CORPORATION OF PENNSYLVANIA.

DESIGN FOR A CABINET FOR RADIOMACHINES.

Application filed July 28, 1922. Serial No. 3,231. Term of patent 3½ years.

To all whom it may concern:

Be it known that I, HARRY C. NAILL, a citizen of the United States, residing at Hanover, in the county of York and State of Pennsylvania, have invented a new, original, and ornamental Design for Cabinets for Radiomachines, of which the following is a specification.

Referring to the drawing—

The single figure of the drawing is a

perspective view of a cabinet for radio machines, showing my new design.

I claim:

The ornamental design for a cabinet for radio machines, substantially as shown.

In testimony that I claim the foregoing as my own, I have hereto affixed my signature.

HARRY C. NAILL.
